UNITED STATES PATENT OFFICE.

GEORGE GOULD GOING, OF MIDDLETON, CONNECTICUT, ASSIGNOR, BY MESNE ASSIGNMENTS, TO REMINGTON-NOISELESS TYPEWRITER CORPORATION, A CORPORATION OF NEW YORK.

TYPEWRITING MACHINE.

Application filed April 9, 1921. Serial No. 459,922.

To all whom it may concern:

Be it known that I, GEORGE GOULD GOING, a citizen of the United States, residing at Middletown, in the county of Middlesex and State of Connecticut, have invented certain new and useful Improvements in Type-writing Machines, of which the following is a full, clear, and exact description, such as will enable other skilled in the art to which it appertains to make and use the same.

This invention relates to typewriting machines and in some of its details particularly to improved shifting mechanism for varying the relative positions of the platen roller and type so as to bring different rows of characters on the type bars into position to engage the platen roller.

It is an object of the invention to provide improved shifting mechanism of the class mentioned which is simple and inexpensive in construction and positive, accurate and silent in operation.

It is a further object to provide in a mechanism of the class mentioned, an improved means for positively locking the case shiftable member, in normal operative position and which is releasable by the shift operating mechanism.

It is a further object to provide a shifting mechanism of the class mentioned with improved mechanism for holding the case shiftable frame or member in normal position and for limiting the shifting movement thereof in either direction.

Another object is to provide an improved anti-friction bearing mechanism for guiding the case shift frame of typewriting machines.

Other objects will be in part obvious in connection with the following detailed description of the invention, and in part pointed out therein.

The invention accordingly consists in the features of construction, combinations of elements and arrangement of parts which will be exemplified in the construction hereinafter set forth, and the scope of which will be indicated in the following claims.

An illustrative but preferred embodiment of the invention is shown in the accompanying drawings wherein;

Figure 1 is a top plan view of a typewriting machine embodying the present invention.

tion, certain parts being omitted for a clearness of disclosure.

Fig. 2 is a side elevation of Figure 1 certain parts being shown in section;

Fig. 3 is a detailed fragmentary view showing the locking and stop mechanism, the parts being in position corresponding to the normal operating position of the carriage;

Fig. 4 is a view similar to Figure 3 showing the position of the parts when the case shift frame is moved upwardly;

Fig. 5 is a fragmentary sectional view showing the mounting of the shift shaft; and

Fig. 6 is a detailed fragmentary view showing the ball bearing guiding means for the case shifted member, certain parts being shown in section.

Referring to the drawing for a detailed description of the illustrative embodiment of the invention, a typewriting machine is shown having a frame provided with a base 1 on which the operating parts are supported. A platen carriage 2 carrying a rotatably mounted platen roller 3 is mounted for bodily traveling movement transversely of the frame, being supported in the main for this purpose by an antifriction bearing comprising a hollow ball rail 4 with an open side, a supporting bar being disposed within the ball rail and carried by lugs on the platen carriage extending through the open side of the rail, bearing balls being disposed between the supporting bar and inner surface of the rail. This bearing construction per se forms no part of the present invention but is claimed in a separate application filed by me of even date herewith, now Patent No. 1,522,011, January 6, 1925. Detailed description of such construction is therefore considered unnecessary.

A shiftable type carriage, case shift frame or segment 5 is mounted adjacent to the platen carriage so that type bars (not shown) carried by the former may engage with the platen roller when moved rearwardly. This carriage 5 is mounted for vertical case shifting movement relative to the platen so as to bring the different characters on the type bars in alignment with the impact surface of the platen roller in a manner understood in the art. This mounting

comprises vertically shiftable hollow bearing members or ball rails or guides 6 spaced apart and secured to and supported by a member 7 of the case shift frame. There are preferably two of these guide members of similar construction, but it is obvious that more or less may be used. Each ball rail is provided with an open side having three internal ball races for receiving balls 8. The latter contact on three sides with a vertical fixed bearing or guide rod 9 received within the associated member 6 and connected by a projecting plate or lug 10 of the frame structure 11. The plate 10 is seated and secured within a slot in the rod 9 providing a firm structure to guide the type carriage in its vertical movement. Each set of these balls are retained in position by means of a ball separator or cage 12 adapted to support them in spaced relationship to provide bearings along the companion member 6 and rod 9 so as to support the carriage firmly in accurate alignment at all times. Each ball separator is provided with an extension 13 having a pin 14 engaging a slot disposed intermediate the ends of a lever 15 pivoted at one end to the frame 11 and having its opposite end forked for engagement with a moving part of the case shifting mechanism. The purpose of this construction is to adjust the separators in accordance with the extent of rolling movement the balls receive when the case shift frame is shifted, causing the separators to travel in unison with the balls and avoiding undue friction. To aid in obtaining this result each ball separator is connected to the lever 15 intermediate the ends thereof whereby the throw of the cage is less than the movement of the shift frame. For shifting the carriage or case shift frame 5 vertically in either direction operating mechanism controlled by finger keys 17 and 18 is provided, two keys 17 and two keys 18 being employed in the present instance at opposite sides of the machine. Each key has a locking member 19 pivoted thereto for holding the keys depressed and urged by a spring 20 away from locking position. Each locking member has an inclined notch 21 in the shank thereof adapted to engage the correspondingly inclined edge of the plate 22 when depressed and simultaneously moved rearwardly. It will be understood that the locking mechanism will be held in locking position against the tension of spring 20 by engagement of the inclined notch with the edge of the plate 22, the pressure exerted by springs 23 and 24 on the keys tending to return the same to normal position after being depressed and thus holding the locking button or key in locking position until manual release is accomplished by depressing the key 17 or 18, or by depressing the locking key and moving it from locking position.

A shaft or rod 25 extended transversely of the typewriter frame is rotatably supported in arms 26 pivoted to standards 27 secured to the base plate 1. Shaft 25 is provided adjacent opposite ends with double crank arms 28 secured rigidly thereto each having a forwardly extending portion 28^a and a rearwardly extending portion 28^b each carrying rollers 29 adapted to contact with the shift key 17 or 18. Links 30 are connected at spaced portions of the shaft 25 and to the carriage or case shift frame 5, each link being provided with an offset 31 having an adjustable pin, lug or stop 32. A locking plate 33 is pivotally mounted adjacent each shift link 30 to a bracket 34 secured to the base plate 1 and pressed to normal locking position by a spring 35. Each of these locking plates is provided with a lug or projection 36 extending from one edge thereof, and disposed adjacent thereto is a cam member 37 rigidly mounted for rotation with the shaft 25. Each locking plate 33 is also provided near its upper end with a locking recess 38 having square lateral edges, and spaced from this recess on the opposite sides thereof are upper and lower lugs or stops 39 and 40.

The lug 32 is adjustable in a vertical slot 32^a in the offset 31 to provide adjustment with respect to locking recess 38 and limit stops 39 and 40. To aid in adjustment of each lug 32 a thin plate 32^a is pivoted to the associated link 30 and has a slot 32^b in an angularly disposed portion thereof. This slot is straight or curved eccentrically to the pivot point of the corresponding plate 32^a. Rocking of each plate on its pivoted point when the associated lug 32 is loosened will adjust the latter vertically in its slot and support the same in position until tightened.

Each shift key 17 is pivoted near its rear end at 41 extending to the forward portion of the machine and lying in position to contact with the roller 29 of associated arm 28^a. Each key 18 is pivoted intermediate its ends at 42 having a rearwardly extended portion 18^a lying in position to contact with the under side of roller 19 an arm 28^b. Springs 43 are each connected at one end to parts of the frame and at the opposite end to one of the forwardly extending arms 28^a, the springs being tensioned to support the said arms and functioning in the operation of the locking mechanism in a manner hereinafter described. The lower ends of these springs may be adjustably connected to the arms 28^a at different distances from the shaft 25, a series of openings 44 being provided in the arms 28^a for this purpose.

The operation of the carriage shifting mechanism is as follows: Supposing the parts to be locked in normal operating position as shown in Figs. 2 and 3 and it is

desired to shift the type carriage or shift frame to position to bring another row of characters on the type bars, figures for example, into writing position, either one of keys 18 is depressed against the tension of spring 23, thus exerting through such extension 18^a of the key, pressure on the roller 29 on associated arm 28^b. Since at this time the carriage 5 and shift shaft 25 are locked in position against upward or downward movement by engagement of the pins 32 in recesses 38 of the locking plates 33, the first effect of depressing the key is to impart a slight rotatory movement to the shift shaft 25 in its bearings in the supporting arms 26 against the tension of the springs 43. This initial movement of shift shaft imparts corresponding movement in a counter-clockwise direction to the lock-operating cams causing the latter to engage lugs 36 on the locking plates 33 and forcing the same against the tension of springs 35 into position to disengage the locking pins from slots 38. This releases the carriage to upward or downward movement. Further depression of the key 18 results in bodily movement upwardly of the shaft 25 the same swinging with its supporting arms 26 about the pivotal points thereof. It will be noted in this connection that the tension of springs 43 is sufficient to support the arms 28^a in such a manner as to cause the upward movement of the carriage 5 as depression of the key continues. The shifting movement of the carriage 5 is stopped in upward limiting position by engagement of the pins or stops 32 with the upper limit stops 39 of the locking plates, the elements assuming positions shown in Fig. 4. It will thus be seen that shaft 25 is adapted to be given rotatory movement, prior to movement of the carriage 5, to unlock the latter and to be given subsequent bodily movement to shift the carriage into a new position.

If the carriage 5 is to be moved downwardly, as when it is desired to write capitals, either one of the keys 17 is depressed against the tension of its spring 24, the key engaging roller 29 of the associated arm 28^b and imparting to the shift shaft 25 an initial rotatory movement in counterclockwise direction causing the cams 37 as before to move the locking plates 33 into carriage releasing position. Continued actuation of the key 17 causes the shaft 25 to move downwardly with its pivotal supporting arms carrying with it carriage 5. Movement in this direction is limited by engagement of the pins 32 with the lower limit lugs 40 of the plates 33. During this final movement arms 28^b fulcrum through roller 29 on extensions 18^a of the keys 18 as will be obvious.

After movement in a downward direction 65 and upon releasing the depressed shifting

key 17, the carriage is automatically returned to normal or middle position by action of springs 43, or by gravity when the carriage has been shifted to its upward position and the depressed key 18 has been released. The locking of the carriage 5 in normal position occurs automatically when the locking pins 32 align with the locking recesses 38 in plates 33, the latter being urged into locking position by springs 35. It will therefore be seen that the carriage is positively locked in its normal operating position after having been shifted in either direction, and it cannot be moved from this position without retracting the locking plates 33 which can only be accomplished through initial operation of one of the shift keys as above described.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is—

1. In a typewriting machine, in combination, a type carriage and an adjacent platen carriage, means for shifting one of said carriages relative to the other, means for positively locking the shiftable carriage in normal position, and means rotatively mounted in said shifting means provided with an eccentric member disposed adjacent said locking means, and arranged to displace the same from locking position upon the initial rotation imparted by the actuation of said shifting means.
2. In a typewriting machine, in combination, a type carriage and an adjacent platen carriage, means for shifting one of said carriages relative to the other, means for positively locking the shiftable carriage in normal position, and means rotatively mounted in said shifting means provided with an eccentric member disposed adjacent said locking means, and a rigidly secured lever extraneously fulcrumed through which the shifting movement is applied.
3. In a typewriting machine, in combination, a type carriage and an adjacent platen carriage, means for shifting one of said carriages relative to the other, means for positively locking the shiftable carriage in nor-

mal position, spring returned means rotatively mounted in said shifting means and adapted to be forced against its spring during the initial movement of the shifting means and provided with a member disposed adjacent said locking means and adapted to be rotated when the shifting means is actuated and to impart a movement to release said locking means, and means for positively limiting the shift movement of said shiftable carriage.

4. In a typewriting machine, in combination, a type carriage and an adjacent platen carriage, means for shifting one of said carriages relative to the other, means for positively locking the shiftable carriage in normal position, means rotatively mounted in said shifting means and including a spring returned shaft having cams thereon, said shaft being adapted to be forced against its spring during the initial movement of said shifting means and to impart a rotary movement to said cams, said cams being arranged thereby to release said locking means and permit a shift movement of translation to be imparted to the shiftable carriage.

5. In a typewriting machine, in combination, a carriage for said machine, means for supporting and locking said carriage in normal operative position, and means for shifting said carriage from normal position into an auxiliary position, said means including a member adapted to be given a movement of rotation to release said locking means and a movement of translation to shift said carriage.

6. In a typewriting machine, in combination, a carriage for said machine, means for supporting and locking said carriage in normal operative position, means for shifting said carriage from normal position into an auxiliary position, said means including a member adapted to be given a movement of rotation to release said locking means and a movement of translation to shift said carriage, said shifting means being adapted to shift said carriage in either direction from its normal or initial position.

7. In a typewriting machine, in combination, a carriage for said machine, means for supporting and locking said carriage in normal operating position, means for shifting said carriage from normal position into an auxiliary position, means for positively locking said carriage in the normal position, means rotatably mounted in said shifting means provided with an eccentric member disposed adjacent said locking means and arranged to impart a movement to said locking means in a direction transverse to the shifting movement whereby said locking means is released, and means for automatically returning the carriage to the normal position.

8. In a typewriting machine, in combina-

tion, a carriage for said machine, means for supporting and locking said carriage in normal operating position, means for shifting said carriage from normal position into an auxiliary position, means for positively locking said carriage in the normal position, means rotatably mounted in said shifting means, provided with an eccentric member disposed adjacent said locking means, and arranged to impart a movement to said locking means in a direction transverse to the shifting movement whereby said locking means is released, and means for automatically returning the carriage to the normal position, and arranged to actuate said locking means upon the return movement.

9. In a typewriting machine, in combination, a type carriage and a platen carriage, means for shifting one of said carriages relatively to the other, means for positively locking said shiftable carriage in normal position, means rotatively mounted in said shifting means and provided with a member disposed adjacent said locking means adapted to be rotated when said shift means is actuated and arranged thereby to release said locking means, means for automatically returning said carriage to and locking the same in normal position upon the return of the carriage, and means for positively limiting the shift-movement.

10. In a carriage shifting mechanism for writing machines, in combination, a carriage, a member operatively connected to said carriage to shift therewith, means for positively locking said carriage in a predetermined position, means rotatively mounted in said shifting member and provided with an eccentric member disposed adjacent said locking means, and means adapted to be given an initial rotative movement to said rotatively mounted means to release said locking means and subsequently impart a shift movement of translation to said shiftable member and carriage, said locking means being arranged to limit the shift movement of said carriage.

11. In a carriage shifting mechanism for writing machines, in combination, a carriage, a shaft rotatively mounted and connected to said carriage, a cam and an extraneously fulcrumed lever rigidly disposed on said shaft, locking means cooperating with the shift mechanism to secure said carriage in a predetermined position, and means adapted initially to rotate said shaft to cause said cam to engage with said locking means to release the carriage from the locked position.

12. In case shift mechanism, in combination, a case shift frame, means for locking said frame in normal operative position to the frame of the machine, a member rotatively mounted and connected to be shifted with said shift frame, a crank arm connect-

- ed to said member and receiving a case shifting movement therewith, and a key operatively associated with said crank arm to cause the latter to release said locking means 5 while the case shift frame remains stationary and subsequently effect a case shifting movement of said shift frame.
13. In a typewriting or like machine, the combination of a case shift frame, a normally engaged lock for locking the shift frame against shifting movement, case shift mechanism including a single key controlled member shiftable bodily to effect a case shift movement of said shift frame and having an initial independent rotative movement under control of its key, and means controlled by the initial independent rotative movement of said member for releasing said lock.
14. In a carriage shift mechanism, in combination, a carriage, means for shifting said carriage from one operative position to another operative position, a spring pressed pivoted plate having a recess therein adapted to be swung into engagement with a co-operating portion of said shifting means to lock said carriage in a predetermined operative position, said plate being provided with means to limit the shift-movement of said carriage, a rotatable shaft provided with an eccentric member disposed adjacent said spring pressed plate and a rigidly secured lever extraneously fulcrumed, said shaft being mounted in said shift means and adapted to be rotated by the initial part of the shifting movement, and arranged when rotated to displace said spring pressed plate to release said shifting means.
15. In a carriage shifting mechanism, in combination, a carriage means for shifting said carriage from one operative position to another operative position, a spring pressed locking plate having a recess therein, a lug on said shifting means engaging said recess to lock said carriage in operative position, means on said plate to limit the shifting movement of said carriage, and a rotatable arm operated by said shifting means for disengaging said locking means prior to movement of said carriage.
16. In combination, a case shift frame, means for shifting said frame from one case position to another, and ball bearing means for guiding the case shift frame in its shifting movements comprising a vertically disposed hollow ball rail provided with a plurality of ball races and an internal bearing rod, bearing balls interposed between the hollow rail and said rod, and a ball separator having longitudinally spaced ball retaining portions disposed between said hollow member and said bearing rod.
17. In a typewriting or like machine, the combination of a case shift frame, a normally engaged lock for locking the shift frame against shifting movement, case shift
- mechanism including a key controlled spring-returned rock shaft shiftable bodily to effect a case shifting movement of said shift frame and having an initial independent rotative movement, and means controlled by the initial independent rotative movement of said shaft for releasing said lock.
18. In a typewriting or like machine, the combination of a case shift frame shiftable in two directions from a central normal position, a normally engaged lock for locking said shift frame against shifting movement in either direction from said normal position, a rock shaft shiftable bodily in opposite directions from a central normal position to effect a corresponding shifting movement of said shift frame and also having an initial independent rotative movement, means controlled by the initial independent rotative movement of said shaft for releasing said lock, shift keys, and means controlled by one of said keys for first rocking said shaft and then shifting it bodily in one direction from the normal position and for first rocking the shaft and then shifting it bodily in the opposite direction from the normal position by an actuation of another of said keys.
19. In a typewriting or like machine, the combination of a case shift frame, a pair of normally engaged spring returned locking members for locking the case shift frame against case shifting movement, a rock shaft shiftable bodily to effect a case shifting movement of said case shift frame and having an initial independent rotative movement, means controlled by the initial independent rotative movement of said shaft for simultaneously releasing the pair of locking members, and key controlled means for first rocking said shaft and for then shifting it bodily.
20. In a typewriting or like machine, the combination of a case shift frame, a rock shaft that has a bodily shifting as well as an independent initial rotative movement, a normally engaged lock that locks said shift frame and shaft against shifting movement, means controlled by the initial rotative movement of said shaft for releasing said lock, a shift key, and means controlled thereby for first rocking said shaft and for imparting a bodily shifting movement thereto after the shaft and shift frame are released from said lock.
21. In a typewriting or like machine, the combination of a case shift frame shiftable in two directions from a central normal position, a rock shaft shiftable bodily in opposite directions from a central normal position for effecting corresponding shifting movements of said shift frame and also having an initial independent rotative movement in but one direction from the normal, spring returned normally engaged locking

means for locking said rock shaft and shift frames against case shifting movement in either direction from normal position, means controlled by the initial rocking movement 5 of said shaft for releasing said lock, shift keys, and means controlled thereby for first rocking said shaft and then for shifting the shaft bodily, one key shifting the shaft and shift frame in one direction from the normal 10 and the other key shifting said parts in the opposite direction.

22. In a typewriting or like machine, the combination of a case shift frame shiftable in two directions from a central normal 15 position, a rock shaft shiftable bodily in opposite directions from a central normal position for effecting corresponding shifting movements of said shift frame and also having an independent initial rocking movement in but one direction from the normal, a pair of spring-returned locking latches at 20 opposite sides of the machine and normally engaged to prevent a case shifting movement of said shaft and shift frame in either direction 25 from the normal, stops carried by said latches for limiting the case shift movement of said frame, means carried by said rock shaft and controlled by the initial rocking movement thereof to release said locking 30 latches, crank arms extending in opposite directions from said shaft, and key controlled levers one bearing upwardly on one of said crank arms and the other bearing 35 downwardly on the other of said arms, whereby the shaft is first rocked and then given a bodily upward or downward movement depending on the particular shift key actuated.

23. In a typewriting or like machine, the 40 combination of a case shift frame, roller bearing guiding means for guiding said shift frame in its case shifting movements, a bearing roller separator, means for shifting said case shift frame including a pivot-

ed arm operatively connected thereto, and 45 connections between said separator and arm nearer the fulcrum of the latter than the connection between said arm and the case shift frame, whereby the separator receives a shorter throw than the shift frame. 50

24. In a typewriting or like machine, the combination of a case shift frame, and ball bearing guiding means therefor comprising a plurality of substantially vertically disposed parallel fixed guide rods, a bearing 55 member partly surrounding each of said guide rods and provided with a plurality of ball races formed therein, bearing balls interposed between each of said raceways and the associated guide rod and bearing 60 against the latter on three sides thereof, a ball separator contained within each bearing member and coating with the bearing balls contained therein, and means for moving said separator a shorter distance than 65 the case shift frame at each case shifting movement of the latter.

25. In a typewriting or like machine, the combination of a case shift frame, and means for limiting the shifting movements thereof 70 comprising a stop member adjustably mounted in a slot on the part that carries it, and means for adjusting said stop comprising a pivoted adjusting plate having an eccentric slot therein in which said stop member 75 is received, an adjustment of said plate camming the stop member in one direction or the other along the slot in which it is mounted depending on the direction of pivotal adjustment of said adjusting plate. 80

In testimony whereof I affix my signature, in the presence of two witnesses.

GEORGE GOULD GOING.
